COVER FOR A FOOD WASTE DISPOSER

Walter C. Pitts, Louisville, Ky., assignor to
General Electric Company

Filed Dec. 6, 1972, Ser. No. 311,594

Term of patent 14 years

Int. Cl. D23—02

U.S. Cl. D55—1 B

Fig. 1

FIG.3

FIG.2

FIG. 1 is an isometric view of a cover for a food waste disposer embodying my new design.

FIG. 2 is a rear view thereof.

FIG. 3 is a top plan view thereof.

The bottom face of the cover for a food waste disposer is planar and unornamented.

I claim:

The ornamental design for a cover for a food waste disposer, as shown and described.
